PRINTING APPARATUS

Charles E. Wooddell, Niagara Falls, N. Y., assignor, by mesne assignments, to The Carborundum Company, Niagara Falls, N. Y., a corporation of Delaware

Application May 19, 1936, Serial No. 80,589

8 Claims. (Cl. 154—54.5)

The present invention relates to a printing accessory useful as a top sheet or draw sheet which may be used to enclose or protect the tympan roll, platen, or packing cylinder of a printing press to support a sheet or web while it is being printed. The invention also relates to printing apparatus comprising such an accessory.

This application is a continuation in part of my copending application Serial No. 670,953, filed May 13, 1933.

Depending upon the type of printing which is being done, the printing art may be divided into two general classifications, in one of which the web or sheet that is being printed is supported upon a hard, substantially unyielding surface called a hard pack impression roll, and in the other it is supported by a soft and yielding surface which is commonly called a soft pack impression roll. The first mentioned class is used for the higher grade of printing, such as books and magazines, where the impression cylinder must be on an exact level or plane with each point of the type or halftone and includes modifications where a rubber blanket is placed around the roll and covered with one or two sheets of manila paper and an outer draw sheet making a medium hard pack; while the latter class is used for printing newspapers or other matter which must be printed without material loss of time and where the soft resilient blanket will allow the high points of the type and halftone to sink into the packing cylinder and allow the shallower portions to print legibly. The present invention is concerned with the first mentioned class, namely, that employing a hard or medium pack impression roll for supporting the material to be printed.

This class or division may be again subdivided, depending upon whether the material being printed is supplied in the form of a continuous web or as individual sheets. Where the sheet material is fed to the printing press in the form of a continuous web, it is customary to employ a press comprising a pair of rotating cylinders between which the web is continuously fed. One of the cylinders carries the type and the other cylinder, which is commonly spoken of as a tympan impression roll or packing cylinder, is used to support the sheet being printed. Where a web is to be printed on both sides, it commonly passes from this first pair of rolls almost immediately between a second pair of rolls where the position of the print roll and the tympan roll is the reverse of that found in the first printing so that the second tympan roll supports the

freshly printed side of the web while the opposite side is being printed. Since the freshly printed surface, which is supported by the second tympan roll, is in direct contact with the outer surface of that roll, it is necessary to supply the roll with a covering top or draw sheet which will not pick up ink from the web and thus offset from the packing cylinder to the freshly printed web.

Understanding of the use of my invention in this type of printing apparatus will be facilitated by reference to the drawing wherein,

Figure 1 is a diagrammatic vertical section of the part of one type of printing press in which my invention may be utilized, and

Figure 2 is an enlarged section of a portion of a coated sheet of paper embodying my invention.

Referring to Fig. 1, which shows diagrammatically the printing of both sides of a web of paper, the paper sheet is indicated at 2 as being fed (for instance from a roll not shown) so that the sheet passes between a printing roll 3 and a tympan roll 5. Ink is supplied to the printing roll 3 in a conventional manner as indicated by the small ink device 4. The tympan roll 5 is provided with an outer covering or top sheet consisting of a sheet of paper 8 provided with a surface coating 9, shown in an enlarged section in Fig. 2.

The web which has been printed on its lower side passes on between a second printing roll 6 provided with inking device 4 and a second tympan roll 7, likewise provided with a top sheet 8 having a specially prepared surface 9. This second tympan roll is commonly provided with a so-called oil wipe which is shown diagrammatically in Fig. 1 as a roll 11. This oil wipe rotates in contact with the top sheet of the second tympan roll and is continually supplied with a thin oil such as kerosene or a mixture of 9 parts benzene and one part machine oil, or other specially prepared oil such as peanut oil, pure paraffin oil, etc. As the oil wipe is common in the art a detailed description of the same is deemed unnecessary.

Referring to Fig. 2, the printing accessory of my invention consists of a sheet of hard, substantially unyielding paper 8, coated with a film of hard, tough, strongly adhesive plastic material. The plastic material may be applied in the form of a solution in a volatile solvent so that upon evaporation of the solvent, a film of the solid plastic material is left deposited upon the surface of the paper and is of a nature to be strongly adherent to the paper.

The plastic material 8 may be any of a number

of materials having the required properties of toughness, resilience and strong adhesion to paper. One material which I have found to be very satisfactory for this purpose consists of a cellulose ester lacquer such as is readily obtainable under the trade name "Duco."

These cellulose ester lacquers commonly consist of a solution of cellulose nitrate together with a suitable plasticizing agent such as dibutyl phthalate which remains in the film of plastic material after the solvents have evaporated and reduces the brittleness of the cellulose nitrate. The lacquers also commonly contain a resin such as gum dammar, mastic, rosin or shellac. These gums or resins are particularly useful in promoting adhesion of the lacquer coating to the surface being coated as well as for increasing the hardness and otherwise improving the characteristics of the film. As the production of lacquers is a well developed art and as my invention is not restricted to the use of any particular cellulose ester lacquer, it is not thought that it is necessary to further discuss the production of lacquers.

Other materials which I have found to be suitable for forming the film of plastic material on the surface of the paper 8 are certain synthetic resins having the required properties of toughness, resilience and adhesion to the paper. One such resin is the copolymer of vinyl chloride and vinyl acetate obtainable commercially under the trade name "Vinylite." Other vinyl resins are highly polymerized vinyl acetate and the product obtained by hydrolyzing a vinyl polymer such as polyvinyl acetate with an aldehyde such as acetaldehyde. These latter resins are obtainable under the trade name "Alvar." Another class of resin which I have found suitable for forming the surface film 9 consists of oil-modified phenolic condensation products which are obtainable by reacting a drying oil, for instance tung oil, with a phenol and subsequently reacting the product so obtained with a methylene body such as formaldehyde or hexamethylenetetramine. These products are both heat reactive and oxidizable, and should be applied in the form of solutions of the heat reactive material and subsequently baked to develop the hardness and toughness obtainable when they are properly cured.

Still another class of resin which makes a good film for use in my invention comprises the so-called oil-modified alkyd resins. Alkyd resins as a class are the esters obtained by reacting a polyhydric alcohol with a polybasic acid. The so-called oil-modified alkyds are obtained by replacing part of the polybasic acid by the fatty acid of a vegetable oil, preferably a drying oil such as linseed oil or tung oil. These oil-modified resins are both oxidizable and heat reactive and when baked, set up to form hard, tough, adherent films of the character required by my invention. A modification of such resins consists in preparing a resin containing both an oil-modified alkyd resin and a phenolic resin and resins of this class have also been found to be very well suited for use in my invention.

The paper used is preferably a high calendered cylinder paper which is hard, strong and substantially incompressible. Such papers are readily obtainable and are represented by cylinder papers of the type commonly employed in the manufacture of sandpaper.

Having prepared a paper with a film of plastic material by using any of the plastic materials above mentioned, the product is then applied to

the member which is to support the web or sheet being printed, in the conventional manner.

Where the sheet is employed as a top sheet for a first impression roll as exemplified by roll 5, Fig. 1, it is not essential that the outer coating 9 be ink repellent but the principal requirements in this application are toughness, resilience and a strong adherence to the paper. Continued pressure of the type carried on the outer surface of roll 3 tends to puncture such materials as ordinary manila paper or paper covered with a sheet of vegetable parchment glued to a sheet of ordinary paper and thus to prevent the clear, sharp printing which is desired. My films of plastic material, being extremely tough and resilient, are capable of withstanding the repeated hammering and pressing of the points of the type without becoming distorted or otherwise impaired. When my top sheets are used upon a second impression roll as illustrated by roll 7 of Fig. 1, it is necessary that they not only be tough, resilient and adherent, for the reasons as described in the foregoing discussion of roll 5, but they must also be ink repellent so that they will not pick up ink from the freshly printed surface which passes over them.

Since these hard pack rolls are very carefully built up and require many hours of preparation to get them of suitable contour so that the printing will be sharp and clean, my improved top sheets have a great advantage in being impenetrable by ink and consequently protecting the under surface of the roll against exposure to ink. If a top sheet is penetrable by ink, the ink penetrates and gets onto the surface underneath the top sheet, the surface becomes spongy and tends to swell and the roll is correspondingly spoiled and must be carefully built up again as by removing the ink soaked area and replacing it with fresh sheets of paper.

As indicated above, my invention is adapted for use in presses which print individual sheets as well as it presses printing continuous webs as described above. Where individual sheets are printed, the type is commonly set on a flat plate and the sheet to be printed is either laid onto a flat surface and the type and the sheet are pressed together much like the closing of a book or the sheet is sometimes temporarily secured to the periphery of a cylinder and the freshly inked type is run under the rotating cylinder, the speeds being synchronized so that the impression is transferred to the sheet on the cylinder.

In either kind of printing it frequently happens that the platen or cylinder which is used to support the sheet which is to be printed is closed up with or passed over the type without a fresh sheet having been inserted. In such a case the press will, of course, make an impression on the draw sheet covering the outer surface of the platen or cylinder which will offset from the draw sheet onto the freshly printed sheet being carried by this impression cylinder. It usually requires about ten sheets to completely remove the ink from the surface of the platen or cylinder so that there is no more transfer or offset to the back of the sheets being printed.

My invention has been found to be particularly useful as a top sheet in presses of this type and especially in the type where the sheet being printed is mounted on the periphery of a cylinder or roll, since the surface may be cleaned by the use of an oil wipe and offset or transfer of the ink from the tympan sheet to the back of succeeding sheets is thus eliminated.

It will thus be seen that in providing a printing accessory in the form of a top sheet consisting of a sheet of hard, unyielding, substantially incompressible paper coated with a film of plastic material which is tough, resilient, strongly adherent to the paper, ink repellent, and capable of withstanding repeated hammering of the type and halftones of the printing press, I have supplied an accessory to the printing trade which 5 represents a distinct advance in the art. As indicated, the invention may be embodied in a number of modifications, examples of which I have given, and it is not to be restricted to any particular modification or embodiment but is to 10 be construed broadly as defined by the appended claims.

I claim:

1. A printing accessory for supporting a sheet to be printed consisting of a sheet of hard and 20 substantially unyielding paper adhesively coated with a tough resilient film of plastic material comprising a synthetic resin.
2. A printing accessory for supporting a sheet to be printed consisting of a sheet of hard and 25 substantially unyielding paper adhesively coated with a tough resilient film of plastic material comprising a vinyl resin.
3. A printing accessory for supporting a sheet to be printed consisting of a sheet of hard and 30 substantially unyielding paper adhesively coated with a tough resilient film of plastic material

comprising a hardened oil-modified synthetic resin.

4. A printing accessory for supporting a sheet to be printed consisting of a sheet of hard and 5 substantially unyielding paper adhesively coated with a tough resilient film of plastic material comprising polyvinyl acetate hydrolyzed by reaction with an aldehyde.

5. A printing accessory for supporting a sheet to be printed consisting of a sheet of hard and 10 substantially unyielding paper adhesively coated with a tough resilient film of plastic material comprising a cellulose ester and a resin.

6. A printing accessory for supporting a sheet to be printed consisting of a sheet of hard and 15 substantially unyielding paper adhesively coated with a tough resilient film of plastic material comprising cellulose nitrate and a resin.

7. A printing accessory for supporting a sheet to be printed consisting of a sheet of hard, strong, 20 substantially unyielding paper having adhering thereto a tough resilient film of plastic material comprising a cellulose ester, a resin and a plasticizer.

8. A printing accessory for supporting a sheet 25 to be printed consisting of a sheet of hard, strong, substantially unyielding paper having adhering thereto a tough resilient film of a plastic material comprising cellulose nitrate, a plasticizing agent and a resin. 30

CHARLES E. WOODDELL.
